United States Patent Office

Des. 179,406

Patented Dec. 18, 1956

179,406

CHAIR GLIDE

Philip D. Becker, Hingham, Mass.

Application January 24, 1956, Serial No. 39,889

Term of patent 14 years

(Cl. D10—6)

FIG. 1.

FIG. 2.

Fig. 1 is a top plan view of a chair glide embodying my new design; and

Fig. 2 is a view in side elevation of the chair glide of Fig. 1.

The characteristic features of the design reside in the portions shown in full lines.

I claim:

The ornamental design for a chair glide, as shown and described.
